US0D1041012S

(12) **United States Design Patent** (10) Patent No.: **US D1,041,012 S**
(45) Date of Patent: ** Sep. 3, 2024

(54) **BLOOD GLUCOSE METER**

(71) Applicant: **GUANGDONG TRANSTEK MEDICAL ELECTRONICS CO., LTD.**, Zhongshan (CN)

(72) Inventors: **Yikang Xiao**, Guangdong (CN); **Zhiping Guo**, Guangdong (CN)

(73) Assignee: **GUANGDONG TRANSTEK MEDICAL ELECTRONICS CO., LTD.**, Zhongshan (CN)

(**) Term: **15 Years**

(21) Appl. No.: **35/516,483**

(22) Filed: **Jan. 10, 2023**

(80) **Hague Agreement Data**

Int. Filing Date: **Jan. 10, 2023**

Int. Reg. No.: **DM/226907**

Int. Reg. Date: **Jan. 10, 2023**

Int. Reg. Pub. Date: **Mar. 3, 2023**

(51) **LOC (14) Cl. 24-02**

(52) **U.S. Cl.**

USPC **D24/169**

(57) **CLAIM**

The ornamental design for a blood glucose meter, as shown and described.

DESCRIPTION

1. Blood glucose meter

1.1 : Front

1.2 : Back

1.3 : Left

1.4 : Right

1.5 : Top

1.6 : Bottom

1.7 : Perspective

1.8 : Perspective

Title of the product incorporating the design; Blood glucose meter; Use of the product incorporating the design: used to measure blood glucose; Essential features of the product incorporating the design: the shape; Drawing or photograph best showing the essential features of the product incorporating the design: perspective view 1.

The broken lines in the drawings represents portions of the blood glucose meter and form no part of the claimed design.

1 Claim, 8 Drawing Sheets
